(57) **CLAIM**

The ornamental design for a bottle, as shown and described.

DESCRIPTION

FIG. 1 is a perspective view of a bottle showing my new design;

FIG. 2 is a front elevation view thereof;

FIG. 3 is a rear elevation view thereof;

FIG. 4 is right side view thereof;

FIG. 5 is a left side view thereof;

FIG. 6 is a top plan view thereof;

FIG. 7 is a bottom plan view thereof; and,

FIG. 8 is a front elevation view of the bottle showing my design.

The broken lines in FIG. 8 represent environmental structure of the bottle and form no part of the claimed design. The remainder of the broken lines in the drawing views depict portions of the bottle that form no part of the claimed design.
